H. G. FRENCH

TOY STRIKING BAG OR THE LIKE

Filed Nov. 9, 1925

UNITED STATES PATENT OFFICE.

HAROLD GREGORY FRENCH, OF SOUTH HAVEN, MICHIGAN.

TOY STRIKING BAG OR THE LIKE.

Application filed November 9, 1925. Serial No. 67,901.

This invention relates to amusement devices and has for its object the provision of a novel device adapted for use as a play bag or, when suspended, as a striking or punching bag, the device being not only of durable while cheap construction but provided with certain specific features highly attractive to the juvenile mind so as to promote its use.

With the above and other objects and advantages in view, the invention consists in the combination and arrangement of parts to be hereinafter more fully described and claimed and illustrated in the accompanying drawings in which.

15 Figure 1 is a perspective view of the device.

Figure 2 is a side or edge elevation thereof.

Figure 3 is a view of the blank from which 20 the handle or suspension member is formed.

Figure 4 is a detail cross-section on the line 4—4 of Figure 1.

Referring more particularly to the drawings, I have shown the device as comprising 25 a body 10 which may be constructed of any suitable flexible material, the exact nature depending upon the contemplated cost though it might be mentioned that cloth, oilcloth, rubber or leather, real or imitation, would be 30 very suitable. This body is represented as being preferably of substantially pear-shape and may, in actual practice, be formed from two properly shaped pieces of material stitched or otherwise secured at their edges, 35 as shown at 11, the resultant bag being stuffed with any suitable material of desired weight.

For effecting suspension, I provide a combined suspending and reinforcing means indicated generally at 12 and formed preferably from a single blank 13 having a rectangular central portion 14 and trapezoidal-shaped end portions 15. The central portion 14 is folded longitudinally along the 45 line 16 and stitched, as shown at 17, and then

folded transversely at its center, as indicated at 18, to define the handle member, the end portions 15 being inserted within the bag or against the inner surfaces of the pieces forming the same and stitched or otherwise 50 secured, as indicated at 19, to strengthen the structure.

To render the device particularly attractive to the juvenile mind, grotesque faces or the like may be painted, printed or otherwise 55 inscribed upon the exterior.

When not suspended, the device may be used in substantially the same manner as the old well known "bean bag" and when suspended by a rope or other equivalent element it gives good service as a punching or striking bag, especially as the grotesque faces will stimulate children to deliver a hearty punch, they consequently getting the benefit of exercise while being entertained. 65

While I have shown and described the preferred embodiment of my invention it is of course to be understood that I reserve the right to make such changes in the construction as will not depart from the spirit of 70 the invention or the scope of the subjoined claim.

Having thus described my invention, what I claim is:

In a device of the character described, a 75 bag having one end of flaring shape, and a supporting handle for the bag formed from a single blank of flexible material having an elongated rectangular intermediate portion and trapezoidal end portions, said rectangular intermediate portion being folded longitudinally to provide a plurality of plies and being folded transversely to define a loop, said trapezoidal end portions being located 80 within the smaller end of the bag and secured thereto in conforming relation to the shape thereof. 85

In testimony whereof I affix my signature.

HAROLD GREGORY FRENCH.
